James A. Karns, Akron, Ohio, assignor to Fawick Flexi-Grip Company, a corporation of Ohio

Application December 14, 1953, Serial No. 28,056

Term of patent 14 years

(Cl. D34—5)

FIG. 1

To all whom it may concern:

Be it known that I, James A. Karns, a citizen of the United States, residing at 974 Greenwood Avenue, Akron, Ohio, have invented a new, original, and ornamental Design for a Golf Club Grip or Similar Article, of which the following is a specification, reference being had to the accompanying drawing, forming a part hereof.

Fig. 1 is a side elevational view of a golf club grip or similar article, showing my new design;

Fig. 2 is a fragmentary cross-sectional view thereof, to an enlarged scale, taken on line 2—2 in Fig. 1; and

Fig. 3 is a cross-sectional view thereof, to an enlarged scale, taken on line 3—3 in Fig. 1.

The grip has the same appearance from all sides. The broken line showing of a shaft and club head is for illustrative purposes only.

I claim:

The ornamental design for a golf club grip or similar article, as shown and described.
